METHOD OF MAKING SHOES

Francesco Laudanno, Brooklyn, N. Y., assignor to
 United Shoe Machinery Corporation, Paterson,
 N. J., a corporation of New Jersey

Application February 14, 1933, Serial No. 656,658

7 Claims. (Cl. 12—142)

This invention relates to methods of making shoes and is illustrated herein with reference to manufacturing shoes having flexible foreparts.

Heretofore many efforts have been made to increase the flexibility of shoes of the type in which the marginal portion of an upper is worked over the bottom of a last and an outsole then attached to the overlasted upper. This has been done either by eliminating the insole altogether, by using a very thin insole, or by skeletonizing the insole by removing the central portion of the forepart before the insole was attached to its last. It is, of course, desirable to provide an insole in a shoe of this type not only to facilitate the manufacturing operations, particularly lasting, but also to insure that the shoe will have a smooth interior and that the marginal portion of the upper will be supported against upward strain.

20 An object of this invention is to provide an improved method of making shoes by the practice of which a shoe of the type referred to having a flexible forepart may be produced.

25 A further object of the invention is to facilitate the manufacture of shoes having flexible foreparts by that method in which a cemented upper is secured in lasted position to a lip on the insole and, after the cement has set, the lip and the portion of the upper secured thereto are removed.

30 With these objects in view, the method in one aspect is characterized by the removal of a substantial part of the thickness, but not the entire thickness, of the portion of the insole forward of the ball line at a stage in the manufacture of 35 the shoe subsequent to the lasting operation, that is, at a time after the upper and insole have been assembled upon a last and the upper worked into lasted relation to the insole and secured thereto.

40 In another aspect, the method comprises working the marginal portions of an upper over a laminated insole upon a last, securing the upper in lasted position to the insole, and, after the upper has set in lasted position, removing one 45 of the laminations of the insole, for example the outer lamination.

45 Preferably and as illustrated, the insole is first provided with an outside channel, for example, by cutting in from the edge face of the insole 50 in a plane parallel to the bottom of the insole far enough to provide a wide feather and turning up the outer flap so formed to provide a lasting lip. For this purpose an insole of substantial thickness is required, for example, one three or 55 four irons in thickness. This cut is preferably

made at the joint between two of the laminae of the insole which may be, for example, half way through the thickness of the insole, the marginal portion of the outer lamina being turned up to form the lip. The insole and upper are then 5 assembled upon a last. Cement is introduced between the layers of the upper materials and between the upper materials and the feather of the insole. The upper is then worked into lasted 10 position and secured to the lip of the insole, for example, by staples. The lip and the central portion of the insole should have sufficient strength adequately to withstand the strain of the lasted upper. After a sufficient time has elapsed so that the upper has been "fatigued" and the cement 15 has set sufficiently to hold the upper in lasted position, the insole and the portion of the upper secured thereto, including the staples, are trimmed off flush with the overlasted portion of 20 the upper. The strong lip and the central portion of the insole have now served their purpose in retaining the upper in lasted position until the cement has set and the shoe has reached a stage in its manufacture such that the thickness of the insole may be safely reduced. Accord- 25 ingly, a cut is made along the ball line through the outer lamina of the insole and this outer lamina is pried up and stripped off from the forepart of the shoe, thus reducing the thickness of 30 the insole by the thickness of the lamina so removed. The shoe may then be completed by any 35 of the usual methods.

In the drawing.—

Fig. 1 is a perspective view of the laminated insole employed in the present method;

Fig. 2 is a transverse sectional view of a shoe made by the present method after the lasting operation;

Fig. 3 is a view of the shoe, similar to Fig. 2, after the upper, lip and staples have been trimmed off;

Fig. 4 is a perspective view of the shoe illustrating the step of removing the outer lamina of the forepart of the insole; and—

Fig. 5 is a transverse sectional view of the shoe 45 after the outsole has been attached.

In carrying out my improved method of making shoes in which an outer lamina of the insole is removed after the lasting operation to provide a 50 flexible forepart, an insole such as that illustrated in Fig. 1 is preferably employed. The substance of which the insole is composed, while practically homogeneous, is such that it may be separated into distinct layers. In Fig. 1, one of the layers 55

into which the insole may be separated is indicated at 10 and another at 12, these layers together providing the substantially homogeneous body portion of the insole 14. Insole material having these desirable characteristics is readily available. One such material, consisting mainly of paper pulp and rubber latex formed into sheets, two or more of which are superposed and caused to adhere to each other, has been marketed extensively for several years past under the trade name of "Onco". The insole may be channeled as illustrated to provide a feather portion 16 and a lip 18 extending from the breast line about the periphery of the insole to the breast line again. The insole 14 and an upper 20, ordinarily including a lining 21, are assembled upon a last 22 and the shoe lasted by the practice of the method disclosed in applications for Letters Patent of the United States Serial No. 386,097, filed August 15, 1929, and Serial No. 576,342, filed November 20, 1931, both in the name of George Goddu. By this method cement is applied to the feather of the insole and to the opposed marginal surfaces of the layers of upper material at the sides of the shoe, including usually the inner face of the lining. The upper is worked into lasted relation to the insole and is fastened by staples 24 (Fig. 2) to the lip 18, the upper lying flat against the feather 16 of the insole. The toe and heel portions of the upper are preferably lasted in a machine of the bed type, the cemented upper at the toe being held in lasted position while the cement is setting by any suitable means, for example as described in said applications, and the heel-seat being lasted as usual and secured by tacks completely driven and clinched on the iron heel plate of the last. After sufficient time has elapsed for the upper to become fatigued and the cement to become set sufficiently to hold the upper in lasted position, the lip 18 and the portion of the upper materials secured thereto are trimmed off flush with the bottom of the central portion of the insole, as illustrated in Fig. 3, the staples 24 being, of course, removed at the same time. A steel shank piece 26 may be secured to the shank portion of the insole, as illustrated in Fig. 4. A portion of the insole may now be removed in accordance with my invention. This is preferably done by making a cut 28 along the ball line of the insole through the outer portion thereof and peeling off the outer lamina 30 of the insole, that is, the portion of the layer 12 lying forward of the cut 28, and covering the area inside the inner edge of the overlasted marginal portion of the upper.

If the outsole is to be attached by cement, the overlasted marginal portions of the upper material may now be roughened and cemented, and an outsole 32, also roughened and cemented, may be attached to the shoe in the manner usual in the manufacture of compo shoes, no filler being employed except possibly a thin piece 34 of material, for example fabric, between the insole and outsole to eliminate squeaking. Of course, if desired, the last may be removed and the outsole attached to the shoe by through-and-through stitching, either chain or lock stitches.

When shoes are made in this manner over turn lasts the bottoms of the foreparts of which have considerable transverse and longitudinal curvature, the elimination of the outer layer of the insole and the filler enables shoes to be made the

bottoms of the foreparts of which are substantially flat.

Having thus described my invention, what I claim as new and desire to secure by Letters Patent of the United States is:

1. That improvement in methods of making shoes in which a laminated insole is secured to a last, an upper assembled upon the last and its margin worked into and secured in lasted relation to the insole, and an outsole attached to the shoe, characterized by the removal of a lamina of the insole forwardly of the ball line of the shoe at a stage in the manufacture of the shoe subsequent to the lasting operation.

2. That improvement in methods of making shoes which consists in securing the marginal portion of a shoe upper in lasted position over the forepart of a laminated insole upon a last, thereafter removing the outer lamina of the central portion of the insole located inside the edge of the overlasted upper, and attaching an outsole to the shoe.

3. That improvement in methods of making shoes which consists in securing the marginal portion of a shoe upper in lasted position over the forepart of a laminated insole upon a last, thereafter cutting through the outer lamina of the insole along the ball line of the shoe, removing the outer lamina of the insole forward of the cut, and attaching an outsole in contact with the overlasted margin of the upper.

4. That improvement in methods of making shoes which consists in assembling upon a last an upper and a laminated insole, working the marginal portion of the upper materials over the inner lamina of the insole, securing it in lasted relation to the insole, cutting through the outer lamina of the insole along the ball line of the shoe, removing the outer lamina from the forepart of the shoe, and attaching an outsole to the shoe in contact with the overlasted margin of the upper.

5. That improvement in methods of making shoes which consists in forming an outside channel upon an insole composed of material which may be separated into laminae, turning up the channel flap to form a lip, assembling the insole and an upper upon a last, providing cement between the opposed surfaces of the upper materials and between the inner surface of the upper materials and the feather of the insole, working the marginal portion of the upper over the feather of the insole into lasted relation to the lip of the insole, inserting metallic fastenings through the upper and the lip to hold the upper in lasted position while the cement is setting, after the cement has set removing the lip and the portion of the upper secured thereto including said fastenings, removing the outer lamina of the insole from the ball line forwardly, and securing an outsole in contact with the overlasted margin of the upper.

6. A method of shoe-making which involves attaching the marginal portion of a shoe upper to a two-ply insole, and removing the outer ply material of the insole at the forepart thereof.

7. A method of shoe-making which involves attaching the marginal portion of a shoe upper to a plied insole and removing the outer ply material of the insole at the forepart thereof inwardly of the attached marginal portion of the upper and in front of the front shank line.

FRANCESCO LAUDANNO.
